US00D821513S

(12) **United States Design Patent** (10) **Patent No.:** **US D821,513 S**
(45) **Date of Patent:** **** Jun. 26, 2018**

(54) **GOLF CLUB HEAD**

(71) Applicant: **Golf Tailor, LLC**, Edmond, OK (US)

(72) Inventor: **Tim Oyler**, Edmond, OK (US)

(73) Assignee: **Golf Tailor, LLC**, Edmond, OK (US)

(**) Term: **15 Years**

(21) Appl. No.: **29/599,237**

(22) Filed: **Mar. 31, 2017**

(51) LOC (11) Cl. **21-02**

(52) U.S. Cl.

USPC **D21/752**

(58) **Field of Classification Search**

(57) **CLAIM**

The ornamental design for the golf club head, as shown and described.

DESCRIPTION

FIG. 1 is a front isometric view of a golf club head showing my new design;

FIG. 2 is a front elevational view of the golf club head of FIG. 1;

FIG. 3 is a rear elevational view of the golf club head of FIG. 1;

FIG. 4 is a right side elevational view of the golf club head of FIG. 1;

FIG. 5 is left side elevational view of the golf club head of FIG. 1;

FIG. 6 is top plan view of the golf club head of FIG. 1; and,

FIG. 7 is a bottom plan view of the golf club head of FIG. 1.

The features shown in broken lines in the drawing depict portions of the design that form no part of the claimed design.

1 Claim, 5 Drawing Sheets
